UNITED STATES PATENT OFFICE

164,573

LAMP BASE

Martin S. Hayden, Chicago, Ill.

Application June 9, 1951, Serial No. 15,480

Term of patent 14 years

(Cl. D48—20)

To all whom it may concern:

Be it known that I, Martin S. Hayden, a citizen of the United States, residing at Chicago, in the county of Cook and State of Illinois, have invented a new, original, and ornamental Design for a Lamp Base, of which the following is a specification, reference being had to the accompanying drawing, forming part thereof.

Fig. 1 is a front elevational view of a lamp base showing my new design.

Fig. 2 is a rear elevational view.

Fig. 3 is a side elevational view.

I claim:

The ornamental design for a lamp base, as shown.

MARTIN S. HAYDEN.
